UNITED STATES PATENT OFFICE.

VICTOR ODQUIST, OF YONKERS, NEW YORK, ASSIGNOR TO AMERICAN CAN COMPANY, OF NEW YORK, N. Y., A CORPORATION OF NEW JERSEY.

METALLIC SPOOL.

Application filed May 14, 1923. Serial No. 638,720.

The present invention relates to metal spools and has as a principal object the provision of a spool of such strength as to be adapted to hold silk thread without yielding 5 to the unusual strains to which it is subjected when said thread is wound thereon.

In practice, considerable difficulty has been experienced with the types of metal spools used for this purpose, due to lack of 10 strength and to relative movement between the parts employed. It will be understood that the thread must be wound under considerable tension and the elasticity in silk thread, when multiplied many thousands of 15 times by the many loops when in position, results in a very powerful breaking strain. All other types of metal spools, of which I am aware, have, for this reason, been inadequate, not only for silk thread, but have 20 not even proved to be of sufficient strength to hold a good grade of cotton thread. As a consequence, wooden spools have been customarily employed for this type of thread and the present invention is directed to the 25 provision of a metallic spool which will be as strong as a wooden spool, or stronger, and which can be economically manufactured.

A further object of the invention is the provision of a relationship between the 30 parts of a metallic spool which will prevent the crowding of the thread between the core and end members, or walls, and in which said walls are positively held against relative movement with respect to the other 35 parts employed.

Other objects and advantages of the invention will be apparent as it is better understood from the following description, which, taken in connection with the accompanying drawings, discloses a preferred embodiment thereof.

Referring to the drawings,

Figure 1 is a side elevation, partially broken away and shown in section, of a 45 metallic spool embodying the principles of my invention;

Fig. 2 is an end elevation thereof; and

Fig. 3 is a transverse section, taken substantially on the line 3—3 in Fig. 1.

The spool which I have illustrated in the drawings, as a preferred exemplification of the invention, comprises a main exterior core member 21 and a second and smaller core member 22, to which are secured, respectively, end walls 23 and reinforcing

plates 24 which are interengaged, as will be hereinafter described.

The core member 21, has its longitudinal edges joined in a side seam 25, which is formed by hooking said edges about each 60 other with one edge bent inwardly, as shown at 26, whereby the seam is disposed interiorly, leaving a smooth exterior surface upon which the thread may be wound.

The walls 23 are secured to the ends of 65 the core member 21 by means of interengaged flanges, as shown in section in Fig. 1. Said wall members 23 are centrally apertured and adapted to fit over the member 21. The inner edges of said wall members are 70 provided with flanges 27, which are bent from the plane of the wall proper on a sharp line of bend 28 and which engage the surface of the core member throughout a considerable area. As will later appear, these 75 flanges are held tightly against said core member and the construction just referred to effectually prevents the packing of the thread between the parts. The flange 27 is turned upwardly at its outer edge, as shown at 29, and the edge 31 of the core member is curled about the upwardly turned part of the flange whereby the wall parts are held 80 firmly in place.

The interior core member 22 is of cylindrical form, the edges 32 thereof being merely brought to adjacent relationship, as shown in Figs. 2 and 3. The ends of said member 22 are flanged outwardly, as indicated at 33, and engage the inner extremities 85 of the reinforcing plates 24, which latter are formed with circular channels 35 fitting over the curled edges 29 of the core member 21, whereby the inner edges of said reinforcing plates are connected with each other 90 independently of the core 21. Said reinforcing plates 24 are beveled inwardly, as indicated at 36, beyond the point of engagement with the core member 21 and the outer edges 37 thereof are curled within correspondingly curled edges 38 on the wall members 23. The extremities of said edges bear 95 against the outer surface of the plates 24, forming a closed seam, or bead, and, since the edges 37 and 38 are curled together, they are each firmly held against relative movement. In this manner, an interlocking 100 relationship is provided, which prevents the creeping of one member upon the other and this, in large measure, contributes to the ad-

vantageous results which I obtain with the present construction, which under practical tests, has been found to fully meet the requirements of service.

5 It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

10 15 I claim:

1. A metal spool comprising in combination an outer core having its end edges flanged outwardly, end walls encircling the core and interlocked with said flanged

edges, reinforcing plates having their margins interengaged with the margins of said end walls, and bearing inwardly against the end flanges of the outer core, and an inner core fitting into said reinforcing plates and having end flanges engaging on the outer 25 sides of the reinforcing plates.

2. A metal spool comprising in combination an outer core having its end edges flanged outwardly, end walls encircling the core at the inner sides of said flanged edges, reinforcing plates having their margins interengaged with margins of said end walls and arranged and bearing against the outer sides of said flanged edges of the outer core, and an inner core fitting into said reinforcing plates and having end flanges engaging on the outer sides of the reinforcing plates.

VICTOR ODQUIST.
